UNITED STATES PATENT OFFICE.

NORRIS ELMORE CLARK, OF PLAINVILLE, CONNECTICUT, ASSIGNOR TO THE NATIONAL METAL FABRIC COMPANY, OF NEW YORK, N. Y., A CORPORATION OF NEW YORK.

EXPANDED-METAL MANUFACTURE.

947,794.

Specification of Letters Patent.

Patented Feb. 1, 1910.

Application filed July 29, 1907. Serial No. 386,004.

To all whom it may concern:

Be it known that I, NORRIS ELMORE CLARK, a citizen of the United States, residing at Plainville, county of Hartford, Connecticut, have invented certain new and useful Improvements in Expanded-Metal Manufacture, of which the following is a full, clear, and exact description.

My invention relates to improvements in expanded metal and the art of manufacture.

In my former patent No. 788,093 dated Apr. 25, 1905, I have described a method of forming expanded sheet metal which consists in first slitting, then expanding and then rolling the sheet. In that case the material was rolled longitudinally of the openings so that the strands were greatly elongated, and being worked cold, the elastic limit was increased. This method has its advantages and the product is valuable particularly where a continuous bond from end to end of the strip is desirable. Such rolling action, however, while it elongates the strands, does not materially affect the widths of the strands, and in fact does tend to close the openings and narrow the strip. I have discovered that the sheet may be both elongated and widened by rolling it transversely—that is,—across the narrow way of the mesh and so as to reduce the gage. This causing the metal to flow across the bonds and strands gives an increased elastic limit, so that the material has greater strength to resist tearing at the bonds, and greater stiffness to resist collapse when tension is applied longitudinally of the strands. These advantages are attained in degree even when the reduction is very slight, provided the material is rolled across the strands as distinguished from lengthwise of the strands, as in my former patent. Longitudinal rolling seems to draw the strands together and closes the openings, whereas transverse rolling takes advantage of the truss-like formation of the strands and increases both dimensions of the openings. Certain of the advantages in method and product may be obtained by rolling punched stock, provided the openings are elongated in form and the rolling is done transversely. Where the direction of length of the openings before rolling corresponds with the length of the strip,

the improved action and product may be secured by using two pairs of rolls having their axes inclined or converging forwardly in the direction of feed of the strip, so that they draw the strip forward and at the same time stretch and smooth it laterally. When the gage of the material is to be reduced to any great extent, it is preferable to accomplish the reduction by stages, first passing the stock forward through the rolls and then backward, so as to produce a more uniform action and appearance.

Figure 1 is a plan view of a fragment of material illustrating my invention during the reducing action. Fig. 2 is a sectional view of the same, showing fragments of rolls in the act of reduction.

The stock 1, to be treated according to my improved method is illustrated at the left of the line $\alpha-\alpha$ Fig. 1, and after treatment by the rolls 2 and 3 the product 4 is at the right. The fibers of the metal are drawn in the direction of the rolling action, so that the elastic limit of the metal, especially at the bonds, is increased and the product is better qualified to resist severe stresses. Reducing the gage widens the bonds and strands in the direction of the rolling so that the product may have strands and bonds proportionately much wider than would be possible in thin flat material by any other process. The openings in the stock are widened and lengthened by this process, as before mentioned, and although the increase in length is slight, the area of the product is materially increased.

What I claim is:

1. The method of forming expanded metal which consists in first forming a sheet made up of strands permanently connected together at intervals with openings between and arranged so that the bonds and strands are relatively staggered and then passing the sheet through reducing rolls in a direction transverse to the length of the bonds.

2. The method of forming expanded sheet metal which consists in forming elongated openings in the sheet and then rolling down the sheet transversely to the direction of elongation of the openings.

3. The method of forming expanded sheet metal which consists in providing alter-

nately arranged elongated openings in the sheet and feeding the sheet between reducing rolls transversely to the elongated openings.

4. The method of forming expanded sheet metal, which consists in slitting the stock expanding it and rolling it down at right angles to the ends of the slits.

5. The method of treating slitted sheet metal which includes expanding it and rolling it transversely and increasing its superficial area in two directions.

6. The method of forming expanded metal from a sheet having openings in staggered

arrangement, which includes rolling it and causing the simultaneous widening of the openings and widening the strands.

7. The method of treating a sheet of metal made up of strands and bonds separated by openings, which includes rolling it and simultaneously widening the strands and bonds.

NORRIS ELMORE CLARK.
